UNITED STATES PATENT OFFICE.

FRANK MESKER AND HENRY F. EDWARDS, OF ST. LOUIS, MISSOURI,
ASSIGNORS TO MESKER & BROTHER, OF SAME PLACE.

PLATE-METAL COLUMN.

SPECIFICATION forming part of Letters Patent No. 399,202, dated March 5, 1889.

Application filed November 27, 1888. Serial No. 292,008. (No model.)

To all whom it may concern:

Be it known that we, FRANK MESKER and HENRY F. EDWARDS, of St. Louis, Missouri, jointly have made a new and useful Improvement 5 in Plate-Metal Columns, of which the following is a full, clear, and exact description.

The improvement relates to that type of plate-metal columns which is employed in 10 architectural work—such as building-fronts—and composed mainly of plates or plates and angle-irons riveted together, and usually having ornamental attachments upon the front of the column.

15 The improvement consists in the special shape and combination of the parts composing the column, and in the means for stiffening the column and applying the attachments, substantially as is hereinafter set forth and 20 claimed, aided by the annexed drawings, making part of this specification, in which—

Figure 1 is a view in perspective of the improved column; Fig. 2, a vertical section of the column on the line 2 2 of Fig. 3, which, in 25 turn, is a horizontal section of the column; Fig. 4, a vertical section on the line 4 4 of Fig. 3, looking toward the front of the column; and Fig. 5, a vertical section on the line 4 4 of Fig. 3, looking toward the rear of the 30 column. The last three views are upon an enlarged scale.

The same letters of reference denote the same parts.

The improved unornamented column is 35 composed mainly of three plates, two angle-irons, and two quarter-turn curved angle-irons, combined as follows:

A represents a flat plate, which forms the front of the column.

40 B B' are flat plates forming the sides, respectively, of the column.

C C' represent angle-irons attached, respectively, to the sides B B' at the rear edge and upon the inner side thereof, substantially 45 as shown.

D D' represent the curved angle-irons. They are arranged, respectively, at the front corners of the column. The front plate, A, when in position, is not between the side plates 50 or against the front edges thereof, but is spaced

apart from the side plates, and it stands in front of them, substantially as shown in Figs. 1 and 3, and it is held in place and united to the sides B B' by means of the curved angle-irons, which are applied so that the edge 55 d of the curved angle-iron laps upon the outer face of the front plate, and is riveted to the front plate, and the edge d' of the curved angle-iron laps upon the outer face of the side plate, and is riveted to the side plate. By 60 this means the column at its front corners is both strengthened and ornamented. Another feature of the column is the means for stiffening it.

E represents a flanged plate arranged horizontally within the column and adapted to fit and to be attached to the united side and front plates. It is attached to the plates A B B' by means of the rivets e, which pass through the flange e' of the plate E and through the 70 abutting plate A B B', as shown.

To avoid the fastenings used in attaching the curved angle-irons, and also to make room for the angle-irons at the back of the column, the plate E is scalloped at its corners e², substantially as shown. The portion e³ is preferably made to come between the angle-irons C C', as shown. The plate is preferably made open at its center, e⁴, to lighten it. The plates E are introduced into the column at various 80 levels, as indicated in Fig. 2. They serve as a means for uniting the front and side plates, A B B', irrespective of the curved angle-irons D D'; but they are of especial value, in conjunction therewith, in uniting the plates and 85 in strengthening the column.

F G represent ornamental attachments applied to the column-front. They are fastened thereto by means of the screws or rivets f, which pass through the attachment, and in 90 the case of screws tapped into the column-front, and in the case of rivets passed through both attachment and front. When opposite the plates E, the same rivets used to unite the plate E and column-front may be extended 95 to include the attachment.

We claim—

1. The combination of the front plate, the side plates, the angle-irons at the rear of the column, and the curved angle-irons at the 100

front corners of the column, the front plate being spaced apart from the side plates, substantially as described.

2. The combination of the front plate, the 5 side plates, the angle-irons at the back and the curved angle-irons at the front of the column, and the horizontal stiffening-plates, substantially as described.

3. The combination of the front plate, the 10 side plates, the flanged stiffening-plates, the

curved angle-irons, the angle-irons at the back of the column, and the attachments upon the front of the column, substantially as described.

Witness our hands.

FRANK MESKER.
HENRY F. EDWARDS.
